WILLIAM T. DOYLE, OF DORCHESTER, MASSACHUSETTS, ASSIGNOR TO STURTEVANT MILL COMPANY, OF BOSTON, MASSACHUSETTS, A CORPORATION OF MASSACHUSETTS

METHOD OF AND APPARATUS FOR HYDRATING CELLULOSE PULP

Application filed April 26, 1932. Serial No. 607,528.

This invention relates to the hydration of cellulose pulp for papermaking or the like and has for its object to provide an improved method and apparatus for accomplishing this result as well as for realizing other important qualities in the hydrated pulp.

Before cellulose pulp can be formed into paper of the proper texture, strength, tear resistance, fold endurance, and other physical characteristics, it must undergo a beating operation in water under conditions to hydrate or gelatinize the pulp fibers. The hydrated or gelatinized condition in the pulp fibers means that the paper or other fibrous product made therefrom will have the proper density and "closed in" structure and that the gelatinized cellulose will bond the fibers together so as to lend the requisite mechanical properties to the paper or other fibrous product. The degree to which beating is effected depends upon the kind of cellulose stock serving as raw material as well as upon the qualities desired in the finished manufacture and can be controlled by determining from time to time during the beating operation the so-called slowness value which is considered to be a measure of the degree of hydration or gelatinization.

Heretofore the beating of cellulose pulp has been generally accomplished in a Hollander or beater engine having a roll equipped with knives passing over a so-called bed plate at such a narrow clearance as to brush the fibers circulating past the clearance space. As hydration progressed, the beating was made harder by bringing the knives closer to the bed plate with the result that besides hydration a marked cutting of the fibers ensued. The cutting of the fibers is reflected in a depreciation of such qualities as tear resistance and fold endurance, which are tied up with fiber length, in the finished paper. The foregoing trouble is accentuated when the beaten pulp is put through a Jordan engine which is sometimes employed to complete the hydration of the fibers and which operates on the same principle as a Hollander.

In accordance with the present invention cellulose pulp stock undergoes hydration as a thick aqueous suspension by being re-

peatedly subjected to the action of a so-called hammermill which is designed to individualize the pulp fibers and to hydrate them efficiently and with much less cutting action than that encountered in an engine of the type previously described. In accomplishing this result, it is necessary to maintain a supply or batch of the stock as a thick aqueous suspension, to remove the stock progressively from the supply and to feed it through the hammermill, to return the stock to the supply, and to repeat the cycle until the degree of hydration desired for papermaking has been attained in the stock. More than this, however, in order to realize an efficient hydrating action, it is necessary to feed the stock into a hammermill having a restricted discharge made up of one or more openings from which the water of the pulp suspension may freely flow but designed to permit the accumulation of stock in the mill. The mill is operated to deliver a swift succession of hammering impacts or combing effects on the stock fed thereto but under conditions to discharge forcefully only part of the stock through the exit openings. This means that there is always stock in the hammermill undergoing hydrating action so that the mill operates constantly under load and hence efficiently. It is preferable that the rate of feeding of the stock into the mill be substantially equal to the rate of stock being discharged therefrom so that the mill may operate under a substantially steady load and with no backflow of stock in the system.

In practising the foregoing method, I employ a circulatory channel for keeping a supply or batch of the stock undergoing treatment, e. g., an oval-shaped tub such as forms part of the usual Hollander. Included as part of the circulatory system is the hammermill casing, which has an intake communicating with the supply in the channel and whose outlet delivers the discharged material, including water and stock, back to the channel. The hammermill itself may afford all the circulating action, although, if desired, a pump or other suitable means may be used to promote circulation. From the

standpoint of efficiency, it is desirable that the hammermill operate upon stock of high consistency or thickness. In order to secure good circulation in the system and at the same time to deliver thick stock to the hammermill, provision may be made to thicken the stock near the intake of the hammermill and to dilute the stock at a point remote from the intake so as to avoid sluggishness in the movement of the stock to the intake.

With the foregoing and other features and objects in view, the present invention will now be described in greater detail in conjunction with the accompanying drawings, wherein

Figure 1 represents a plan view of an apparatus embodying the present invention.

Figure 2 is a vertical, transverse section 20 through the hammermill on the line 2—2 of Figure 1.

Figure 3 is an end elevation of an adjustable bearing for the shaft of the hammermill.

Figure 4 constitutes a section on the line 4—4 of Figure 2.

Figure 5 illustrates another form of apparatus embodying the present invention.

Figure 6 is a composite view made up of 30 a fragmentary section on the line 6—6 of Figure 5 and a side elevation of one end of the apparatus.

Referring in detail first to Figure 1 of the drawings, the apparatus shown comprises an oval-shaped tub 1, such as forms part of the ordinary beating engine. Into this tub may be put raw material of any suitable character, e. g., sulphite, kraft, or ground-wood pulp, rag or rope stock, or the like. The pulp may be furnished to the tub as in the form of laps or sheets, together with sufficient water to produce, say, a 5% aqueous pulp suspension. The supply thus furnished makes what may be termed a main circuit around the tub and 40 through the casing of a hammermill shown installed centrally on one side of the tub. The casing, as can be best seen from Figures 2 and 4, is of generally cylindrical shape, and includes an intake opening directly into the main stream of pulp stock and of sufficient size to permit sheets of pulp to pass therethrough into the casing. The casing is made up of an external shell 3, which is lined at spaced zones *a*, *b*, and *c* with curved plates 4, 50 suitably secured to the shell and presenting a series of spaced bars or ribs extending longitudinally of the shell. Between the plates at *b* and *c* are a series of longitudinal slots or openings through the shell, defined by spaced bars 6 anchored at their ends to the end walls 7 of the shell. These openings are shown through an upper side of the shell opposite to the intake opening and serve to permit discharge of the water and stock from 60 the casing over an incline sloping into the

main channel of the tub. A cover or shield 8 shown above the tub and near the discharge openings serves to direct the discharged material into the main channel. The cover may overlap the shell 3 sufficiently to permit bolts 9 to be threaded therethrough and to clamp a curved discharge gate 10 against the shell. By loosening the bolts 9, the gate 10 may be moved to close more or less of the openings and thereby to regulate the volume of material being discharged from the casing. At the intake opening, there is shown a flat plate 11, which is pivoted at its rear end 12 so as to permit its forward end to be adjusted to clear the hammers to the desired extent and hence to regulate the disintegrating or breaking action on sheet pulp or other stock used as a raw material. The desired adjustment of the plate 11 may be made by turning a bolt 13 threaded through the bottom of the tub and engaging under the plate. As shown, the casing further includes a curved plate 14 located between the curved plates at *a* and *b*. The plate 14 can also be adjusted toward and away from the hammers so as to control their breaking action on the stock by turning bolts 15 passing through suitable openings in the shell 3 and in threaded engagement with the plate. The size of the intake opening may be varied by a vertical gate 16, which is normally fixed, but which is slidable in vertical ways formed on the side walls of the tub. The function of the gate is also to regulate the load under which the hammermill is operated during the initial disintegrating or breaking action on the stock as well as during the later stages when hydration is being effected. In other words, the speed at which either initial breaking or hydrating action proceeds is to some extent determined by the gate opening.

The stock introduced into the hammermill undergoes a succession of hammering impacts delivered by successive rows of hammers 17 pivotally mounted in spaced relationship on a suitable rotor. The rotor is made up of a series of annular plates 18, which are assembled alternately with a series of washers 19 on rods 20, which pass therethrough and whose ends are provided as with heads riveted onto the end plates so as to prevent lateral movement of the plates and washers. The plates and washers may be keyed to a shaft 21 passing therethrough and through the end walls 7 of the shell. The inner end of each hammer may be of a thickness corresponding substantially to that of each washer 19, so that they may be fit in between successive plates and their inner ends be engaged by a rod 22 passed alternately therethrough and through the plates. The engagement of the hammers by the rod 22 should preferably be a loose one, so that the hammers, although restrained from lateral movement, can swing freely, the rod being 120

fixed against lateral movement as by cotter pins 23 passing through its ends and engaging the end plates. Each end of the shaft 21 is shown journaled for rotation in suitable bearings in a block 24 maintained on suitable supports. Each block is preferably adjustable both sidewise and vertically, so as to permit the free ends of the hammers to strike any locality inside the casing or to move past 10 with a particular clearance. As shown, each block rests on a pair of superposed plates 25 having inclined contacting faces and capable of being made to slide relative to each other so as to raise or lower the block. Extending 15 from opposite ends of each plate are bolts 26 which pass through brackets 27 and which are engaged at their ends by nuts 28. These nuts can be turned to effect the desired vertical adjustment of the block. A pair of 20 bolts 29 threaded through the brackets 27 so that their ends engage opposite sides of the block can serve as the means for effecting sidewise movement of the block. The shaft 21 may be driven by any suitable means, as by 25 a pulley 30 affixed to one end and deriving its motive power through a belt 31 from any suitable source of power (not shown).

As already stated, the conditions under 30 which the hammermill is operated should be such that stock is always present therein, as this makes for higher efficiency. The stock in the hammermill is of higher consistency than the main body of stock in the tub by virtue of the fact that there is a much greater 35 tendency for the free water to pass through the discharge openings than for the stock. The increased concentration realized in the hammermill will vary, depending upon such factors as the size and number of discharge 40 orifices and the speed at which the mill is run, but in any event, a lower consumption of power for a given amount of hydration is realized as a result of the increased concentration.

45 The pulp suspension may to advantage undergo a thickening immediately before it enters the hammermill. To this end, a hollow drum 32 whose periphery is covered with wire cloth may be caused to rotate partially submerged in the pulp suspension near the intake of the mill. The shaft 320 of the drum 50 may be journaled for rotation in the walls of the tub and be driven by suitable means (not shown). The drum may, as illustrated, 55 be constructed like the usual washer drum, and permit water to pass into its interior and to flow by gravity through an open side, while the thickened pulp picked up on the periphery falls immediately outside the intake of the mill. Inasmuch as the water removed 60 from the stock contains gelatinized cellulose, fiber fragments, and the like, which are valuable paper-making ingredients, this water is preferably used for diluting the 65 stock and increasing its mobility.

As illustrated, the water flows into a tank 33 from which it is withdrawn by a pump 34 and passed through a pipe 35 terminating as a pair of valved outlets 36. These outlets are shown arranged to return the water under 70 pressure at spaced points near that end of the vat opposite to where the drum is located. By directing the water at two or more points in the vat, the stock becomes diluted quickly and uniformly and is impelled as a mass toward the thickening drum. Of course, the diluting water may be returned to the stock in the vat in any other suitable way.

Rather than thickening the stock before 75 it goes into the hammermill, the stock may be pumped into a mill so constructed and arranged as to permit a thickening effect by free drainage of the water through the discharge openings. An apparatus designed 80 according to this principle is depicted in Figure 5 wherein the tub 37 is U-shaped and is equipped with an outlet 38 at one end leading to a centrifugal pump 39 shown operated by a pulley-driven shaft 40. The pump 85 removes the stock from one end of the tub and forces it upwardly through a pipe 41 leading to the intake end of a hammermill 42 which is arranged above the other end of the tub. This hammermill may be of a construction substantially like that previously 90 described excepting that the discharge openings 43 extend longitudinally through the bottom of the casing. It is thus seen that 95 gravitation of the water through the discharge openings as well as forcible flow induced by centrifugal action is had, with the result that immediately upon entering the mill, the stock undergoes dewatering and the mill operates upon a thickened stock. At 100 this point, it may be mentioned that in the case of both the apparatus shown in Figures 1 and 2 and that shown in Figures 5 and 6, the stock constantly present in the hammermill, whether or not it undergoes previous thickening as described, is at a higher 105 consistency than the main supply of stock in the vat. This is, of course, on account of the free flow of water taking place through the outlet of the hammermill and, according 110 to, the dewatering action thereby realized on the stock remaining in the mill. But, as already indicated, this dewatering action is had to a greater degree with the apparatus 115 shown in Figures 5 and 6.

After the apparatus has operated on the 120 stock for a while, the temperature of the stock rises and this rise in temperature continues so that, depending upon prevailing atmospheric temperature, the stock may become quite warm or even hot. The development of a heated condition in stock undergoing a beating or hydrating operation is common to various types of beating equipment, but it is especially true in the case of 125 the apparatus of the present invention under 130

the efficient operating conditions described. Inasmuch as heated stock does not undergo hydration as readily as cool stock and may lead to papers of poorer chemical and physical characteristics, it is preferable to cool the stock as it is undergoing hydration. Cooling may be performed in any suitable way, but as shown in Figures 2 and 6, a portion 44 of the outer shell 3 of the hammermill may be made hollow so as to permit cold water or other cooling medium to be circulated therethrough and thereby to carry away the heat generated by the operation of the hammermill on the stock. More or less 10 of the shell may be jacketed with water or other cooling medium as desired. A cooling effect may also be had by injecting cool, compressed air into the pipe 35, the air further functioning to assist the diluting water 15 in impelling the stock toward the thickening drum.

One of the factors in the design of the hammermill to be given consideration is the size 20 of the discharge openings. As already stated, this size must be correlated with a total number of openings comporting with the maintenance of stock in the hammermill during the operation of the apparatus. If the raw material is of a kind apt to clog the 25 openings, the desired rate of discharge of stock from the hammermill is preferably secured through the use of few, say one comparatively large opening, whereas if the raw material can pass through the openings freely, 30 it is preferable to use a larger number of smaller openings to realize the desired rate of discharge. For example, in the case of sulphite pulp, which is a comparatively fine-fibered raw material, the discharge openings 35 may be of a width of, say, $\frac{1}{2}$ to $\frac{1}{6}$ ", but in the case of rope stock or other coarse-fibered pulp, wider openings of a width of, say, $\frac{1}{8}$ to $\frac{1}{4}$ " are preferably used. In both cases, however, the number of openings or overall opening 40 must be coordinated with a size of opening conducive to the proper rate of discharge of stock from the mill. It might be mentioned that hammermills such as I employ are operated at such high speeds that considerable centrifugal force is developed tending 45 to discharge forcibly the stock through the exit openings. Thus the ends of the hammers may move at a speed of about 7500 feet or more per minute. At such high speed, there 50 is also a tendency for the pulp to be deposited as a layer on the bars constituting the inner face of the mill; and the action of the rapidly moving hammer ends against this relatively stationary pulp layer is evidently to broom 55 and fray the pulp fibers so as to cause their hydration. The mill may be run with the free ends of the hammers clearing the lining of the casing, in which case the friction of the hammers on the fibers induces hydration 60 while preserving largely fiber length. It

is, however, possible to adjust the blades so that they actually strike or contact with the bars of the lining and thereby cut or shorten the fibers much in the same way that this is done in the usual beating or Jordan engine. 70 In most instances, however, it is desired to keep the average length of the fibers used as a raw material as long as possible and at the same time to impart that degree of hydration to the pulp compatible with proper 75 interfelting on the papermaking machine and with the realization of papers of the best mechanical properties. By operating the hammermill with the free ends of the hammers clearing the lining of the casing by 80 about $\frac{1}{4}$ " and with a speed of about 7500 feet per minute at the hammer ends, it is possible to preserve substantially the fiber length of the pulp used as a raw material and at the same time to attain a degree of 85 slowness in the beaten pulp consonant with optimum paper manufacture. The preservation of fiber length is, as already stated, of importance in that long fiber length is accompanied by high tear resistance and folding endurance in the paper, but the hydration of pulp is also essential to the realization 90 of papers possessing the uniformity of texture and of high Mullen or bursting strength. The process and apparatus of the 95 present invention makes for a realization of all these various desiderata.

I claim:

1. A cyclic method of hydrating cellulose pulp stock for papermaking or the like, 100 which comprises preparing and maintaining a supply of such stock as a thick aqueous suspension, progressively removing stock from said supply and feeding it into a casing having an outlet through which the water of said suspension may freely flow but designed to permit the accumulation of stock in said casing, subjecting the stock in said casing to a swift succession of hammering impacts under conditions to discharge forcefully only a portion of said stock through 105 said openings, returning the discharged stock to said supply, and repeating the cycle until the degree of hydration desired for papermaking has been produced in the stock.

2. A cyclic method of hydrating cellulose pulp stock for papermaking or the like, 110 which comprises preparing and maintaining a supply of such stock as a thick aqueous suspension, progressively removing stock from said supply and feeding it into a casing having a plurality of openings through which the water of said suspension may freely flow but designed to permit the accumulation of stock in said casing, subjecting the stock in said casing to a swift succession of hammering impacts under conditions to discharge forcefully only a portion of said stock through 115 said openings, returning the discharged stock to said supply, and repeating the cycle until the degree of hydration desired for papermaking has been produced in the stock.

the step of feeding stock from said supply into said casing at a rate substantially equal to the rate of stock being discharged from said casing until the degree of hydration desired for papermaking has been produced in the stock.

3. A cyclic method of hydrating pulp stock for papermaking or the like, which comprises preparing and maintaining a supply of such stock as a thick, aqueous suspension, progressively removing stock from said supply and feeding it into a casing having an outlet through which the water of said suspension may freely flow but designed to permit the accumulation of stock in said casing, subjecting the stock while in said casing at a consistency higher than that of said supply to a swift succession of hammering impacts under conditions to discharge forcefully only a portion of said stock through said opening, returning the discharged stock to said supply, and repeating the cycle until the degree of hydration desired for papermaking has been produced in the stock.

25 4. A cyclic method of hydrating pulp stock for papermaking or the like, which comprises preparing and maintaining a supply of such stock as a thick, aqueous suspension; progressively removing stock from said supply, thickening it, and feeding it into a casing having an outlet through which the water of said suspension may freely flow but designed to permit the accumulation of stock in said casing; subjecting the thickened stock in said casing to a swift succession of hammering impacts under conditions to discharge forcefully only a portion of said stock through said opening; returning the discharged stock to said supply; and repeating the cycle until the degree of hydration desired for papermaking has been produced in the stock.

5. Apparatus of the class described comprising in combination, a vat for maintaining a supply of cellulose pulp stock as an aqueous suspension, a casing having an intake communicating with the supply in said vat and a plurality of openings of comparatively small width discharging into said vat, a hammermill arranged within said casing to deliver a swift succession of hammering impacts to stock within said casing and to discharge forcefully only a portion of said stock through said openings into said vat, and means for progressively feeding the stock from said vat into said casing at a rate ensuring the operation of said hammermill under load at all times.

6. Apparatus of the class described comprising in combination, a circulatory channel for maintaining a supply of cellulose pulp stock as an aqueous suspension, a generally cylindrical casing in said channel having an intake communicating with the supply in said channel and a plurality of openings of comparatively small width discharging into said

channel, a rotary hammermill arranged within said casing to deliver a swift succession of hammering impacts to stock within said casing and to discharge forcefully only a portion of said stock through said openings into said channel, and means for progressively feeding the stock from said channel into said casing at a rate substantially equal to the rate of stock being discharged from said casing.

7. Apparatus of the class described comprising in combination, a circulatory channel for maintaining a supply of cellulose pulp stock as an aqueous suspension, a generally cylindrical casing in said channel having an intake communicating with the supply in said channel and a plurality of comparatively small openings discharging into said channel, means for thickening said stock adjacent to said intake, a rotary hammermill arranged within said casing to deliver a swift succession of hammering impacts to stock within said casing and to discharge forcefully only a portion of said stock through said openings into said channel, and means for progressively feeding the stock from said channel into said casing at a rate substantially equal to the rate of stock being discharged from said casing.

8. Apparatus of the class described comprising in combination, a circulatory channel for maintaining a supply of cellulose stock as an aqueous suspension, a generally cylindrical casing in said channel having an intake communicating with the supply in said channel and a plurality of comparatively small openings discharging into said channel, a rotary hammermill arranged within said casing to deliver a swift succession of hammering impacts to stock within said casing and to discharge forcefully only a portion of said stock through said openings into said channel, means for progressively removing water from said stock at a point in said channel adjacent to the intake to said casing, means for returning said water at a point in said channel remote from said intake, and means for progressively feeding the stock from said channel into said casing at a rate substantially equal to the rate of stock being discharged from said casing.

In testimony whereof I have affixed my signature.

WILLIAM T. DOYLE.
